Specification for Design.

Patented Feb. 10, 1914.

Application filed September 11, 1913. Serial No. 789,376. Term of patent 3½ years.

To all whom it may concern:

Be it known that I, SIDNEY A. KELLER, a citizen of the United States, residing in the borough of Manhattan, in the county of New York and State of New York, have invented a new, original, and ornamental Design for Lockets, of which the following is a specification, reference being had to the accompanying drawings, forming a part thereof.

Figure 1 is a perspective view illustrat-

ing the obverse of the central element of the design, and Fig. 2, a like view illustrating the reverse of the same.

I claim:

The ornamental design for a locket, as shown.

SIDNEY A. KELLER.
